Frank L. Gale.
ATTORNEY

UNITED STATES PATENT OFFICE

SALLY ROBERTS, OF NEW YORK, N. Y.

ART OF HAIR WAVING

Application filed July 31, 1929. Serial No. 382,399.

My invention relates to improvements in the art of hair-waving.

It is now common practice to wave natural hair on the head by a process known as finger waving which involves the use of a finger of the hand to hold the hair against disarrangement while a suitable instrumentality such as a comb is being used to manipulate or wave the hair.

10 This method is awkward particularly to one waving one's own hair due to the awkwardness involved in properly placing the finger in contact with the hair and due also to interference by other fingers of the hand 15 to the combing operation to form the wave.

Hence the present invention is directed to a method of and means to facilitate waving one's own hair in a manner to overcome the difficulties mentioned and with results even 20 better than is accomplished by the old method.

In the accompanying drawings, Fig. 1 illustrates in perspective, a view of an instrumentality constructed in accordance with the present invention for use in the process of 25 waving the hair; Figs. 2 and 3 are modified arrangements; and Fig. 4 illustrates the method of using such instrumentality.

The invention in one of its simplest and least costly forms, is illustrated in Fig. 1, and 30 consists of an elongated strip or member such as 1 made of flexible and firm material such for example as rubber, leather, chamois, felt, cloth or other suitable materials or compositions of similar nature which in addition 35 to being flexible and firm, must also be of the tenacious order.

As will be observed in Fig. 4, one can very easily and without awkwardness keep the member 1 in firm contact with one's own hair simply by slight pressure of the fingers thereon. Such finger pressure causes the member because of its flexible quality to conform to the slope of the head and it being of the tenacious order will prevent the hair and 40 wave already formed which it contacts with from being disarranged while the hair adjacent the member, or in other words, the un-waved portion thereof, is being manipulated 45 or waved by any suitable instrumentality such as a comb, for example.

From what has been said, it will be observed that one waving one's own hair can keep the member in contact with the hair in a manner so that there is no interference by any fingers of the hand so holding said member, to the 55 combing operation to form the wave, and furthermore, the member being flexible and of the tenacious order results in a clear-cut wave of regularity.

In using the comb or other instrumentality 60 to form the wave, the comb will engage the edge of the member and in time may mutilate the material at such point, and to eliminate this a flexible metallic strip 2 may be provided and affixed to the member by an adhesive or 65 any other suitable means so that the two form a unitary instrument.

The invention according to the modified form illustrated in Fig. 2, is in the form of 70 a flexible metallic strip 3. A plain strip of metal lacks the tenacious quality which is so necessary and important in order that the hair forming a wave already formed, and which the strip contacts with, cannot be disarranged. However, the metal strip with de- 75 pending teeth 4 formed thereon to engage the hair can be used with equal ease and with equally good success as a member of the tenacious order such as rubber, etc.

It is preferable to construct the toothed 80 bend 4 in the strip so that the base 4' of the teeth will be slightly below the bent edge 5 of the strip so that said edge provides a smooth or unbroken face against which a comb may scrape without liability of damage- 85 ing either instrument.

In the Fig. 3 modified arrangement, the member 6 which may be of rubber or leather, etc., as in Fig. 1, instead of having top and bottom faces both flat, as in Fig. 1, may have a 90 bottom face slightly convex in form said face to be held in contact with the hair.

Having thus described the invention, what I claim as new and desire to secure by Letters Patent of the United States is:—

1. An article of manufacture for use in the art of waving hair which consists of a rectangular shaped flexible member normally uncurved as to its length, having a relatively wide hair engaging surface of substantially 100

uniform thickness throughout its width, said member adapted to be held upon the top surface of the user's hair and at the same time flexed by pressure of the fingers of the user
5 spread along the top face of said member to conform throughout its length to the shape of the head, said member thereby defining a boundary from which unwaved hair is combed to form a new wave and being of
10 a quality which inherently causes it to grip the top surface of the hair to prevent that portion of the hair which is already waved from being disarranged by said combing of the hair to form a new wave, one of the side
15 faces of said strip forming a guide for the combing movement.

2. An article of manufacture for use in the art of waving hair which consists of a rectangular shaped strip of rubber normally
20 uncurved as to its length, having a wide hair engaging surface of substantially uniform thickness throughout its width, said strip adapted to be held against the top surface of the user's hair and at the same time flexed
25 to conform throughout its length to the shape of the head, by pressure of the fingers of the user spread along the top face of the strip the latter thereby defining a boundary from which the hair to be waved is combed to form
30 a new wave, and being relatively soft so as to grip the top surface of the hair to prevent that portion of the hair which is already waved from being disarranged by said combing of the hair to form a new wave, one of the
35 side faces of said strip forming a guide for the combing movement.

In witness whereof, I have hereunto set my hand this 29th day of July, 1929.

Mrs. SALLY ROBERTS.
